Primary Examiner — Robert M Spear(74) *Attorney, Agent, or Firm* — Sheridan Ross P.C.(57) **CLAIM**

The ornamental design for a vented container end closure, as shown and described.

DESCRIPTION

FIG. 1 is a front perspective view of the vented container end closure;

FIG. 2 is a top plan view thereof;

FIG. 3 is a bottom plan view thereof;

FIG. 4 is a front perspective view of a vented container end closure according to an alternative embodiment;

FIG. 5 is a top plan view of the embodiment of FIG. 4; and, FIG. 6 is a bottom plan view of the embodiment of FIG. 4.

The broken line showing of a vented container end closure illustrates environment and forms no part of the claimed design. It is understood that the outermost broken line in each drawing figure defines the interior boundary of the claim.
